UNITED STATES PATENT OFFICE.

ANNA GOLD, OF FREDERICKSBURG, TEXAS.

COMBINATION-GARMENT.

1,345,763.

Specification of Letters Patent.

Patented July 6, 1920.

Application filed January 25, 1919. Serial No. 273,000.

To all whom it may concern:

Be it known that I, ANNA GOLD, a citizen of the United States, residing at Fredericksburg, in the county of Gillespie and State of Texas, have invented a new and useful Combination-Garment, of which the following is a specification.

This invention is a garment in which a shirt and a pair of drawers are combined 10 to form a single article of apparel.

One of the objects of the invention is to provide a garment of the character mentioned, so constructed that the drawers will have ample seat room, and the whole so arranged 15 that the garment may be readily put on or removed without rendering it necessary for the wearer to remove his trousers or shoes. A further object is to provide a shirt and pair of drawers combined in one garment which will be comfortable upon the person, and so constructed that the parts may be readily manipulated when being placed on or removed from the body of the wearer.

25 The invention will be hereinafter fully set forth and particularly pointed out in the claim.

In the accompanying drawings:—

Figure 1 is a perspective view of a garment constructed in accordance with the invention. Fig. 2 is a detail sectional view. Fig. 3 is a diagrammatic view illustrating the method of providing fullness in the seat of the garment.

35 Referring to the drawing, 10 designates an upper shirt body provided with the usual sleeves, neck band 11, and front opening 12, said front opening being formed by a closure band 13, and a fastener band 14, all of any preferred construction. The drawers 15 are provided with a waist portion 16, and the leg portions 17 and 18, the waist portion being secured to the corresponding portion of the body 10, in any suitable manner, as indicated at 19. The fly of the drawers consists 45 of a closure band 20 and fastener band 21, both of which form continuations of the bands 13 and 14, respectively.

Both of the legs of the drawers are split 50 longitudinally as shown, the leg 17 being provided with a closure band 22 and a fastener band 23, said closure band extending at an angle to the closure band 20, and forming a sharp corner with the latter at 55 the crotch. The leg 18 is provided with a closure band 26 and a fastener band 27, the

closure band being concealed by a flap 28. The crotch end of the band is located beneath the corner formed by the intersection of the bands 22 and 20, when the garment 60 is in use.

In practice, the fastener band is provided with suitable fastening devices, such as buttons to be engaged by buttonholes or other complementary means on the closure band, 65 and it will be noted that the bands 13, 20 and 22 form a practically continuous band. When the garment is to be worn, the fasteners are all disconnected and then the shirt is put on in the customary manner. 70 The bands 26 and 27 of the leg 18 are then united, after which the closure band of the leg 17, the closure band of the fly and the closure band of the waist or body of the shirt are successively buttoned up, the 75 closure bands at the crotch forming a projecting corner which overlaps the bands of the leg 18, thereby providing a neat fit at this point. In order to provide ample seat room, which is a necessity if comfortable fit 80 of a garment of this character is desired, the seat of the drawers is made full by an addition to the length of the back portion of the drawers. Whereas the usual pattern of drawers shows a straight cut waist band 85 measuring for No. 38 garment from the lower edge of the seat to the upper part of the waist band (line A—B, Fig. 3) approximately 10 $\frac{1}{2}$ inches, the proposed innovation provides for an extension of such back line 90 4 $\frac{1}{2}$ inches (line B—C, Fig. 3) added to the back line so that the upper line of the waist band will run diagonally upward from front to rear on the line D—C, Fig. 3, having the effect of adding a triangular section E to 95 the waist band, thus lengthening the seat portion of the garment. The bands of the legs will come well up inside of the legs of the wearer. This construction also possesses a further advantage in that the buttons are 100 brought to a position where they will not cause discomfort when the wearer is in a sitting posture. When it is desired to remove the garment, the front of the shirt is unbuttoned in the usual way, after which the 105 fly and leg portions are successively unbuttoned. The garment may then be removed without necessitating the taking off of the trousers or removing the shoes, and may be replaced or another garment substituted 110 with but little trouble.

Having thus explained the nature of the

invention and described an operative manner of constructing and using the same, although without attempting to set forth all of the forms in which it may be 5 made, or all of the forms of its use, what is claimed is:—

A combination garment comprising a shirt portion and a drawers portion united into a single integral garment by a waist 10 seam, said shirt portion having a closure band and a fastener band extending from the neck to said waist seam, said drawers portion having a closure band and a fastener band positioned to form continuations of 15 the first mentioned bands from said waist seam to the crotch, whereby a fly is provided at the crotch, the closure band and fastener band of the drawers portion extending lon-

gitudinally along one leg of the drawers from the crotch to the extremity of the leg, 20 the other leg of the drawers being split from the crotch to the extremity of the leg and provided with means for normally closing said split portion, and fastening devices carried by the fastener bands and positioned 25 to be engaged by the closure bands, said waist seam being positioned to extend diagonally upward from the front to the rear to lengthen the seat portion of the drawers, whereby the fastening devices for both legs 30 may position themselves on the inside of the legs of the wearer.

In testimony whereof I have hereunto set my hand.

ANNA GOLD.
